(57) **CLAIM**

The ornamental design for a portion of a display screen with animated graphical user interface, as shown and described.

DESCRIPTION

FIG. 1 is a front view of a first image of a first embodiment of a portion of a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a first image of a second embodiment of a portion of a display screen with animated graphical user interface showing our new design;

FIG. 7 is a front view of a second image thereof;

FIG. 8 is a front view of a third image thereof;

FIG. 9 is a front view of a fourth image thereof; and,

FIG. 10 is a front view of a fifth image thereof.

In the first embodiment, the appearance of the transitional image sequentially transitions between the images shown in FIGS. 1 through 5. In the second embodiment, the appearance of the transitional image sequentially transitions between the images shown in FIGS. 6 through 10. The process or period in which one image transitions to another image forms no part of the claimed design. The broken line showing of a portion of a display screen in FIGS. 1 through 10 forms no part of the claimed design. The broken line showing of text and portions of the graphical user interface in FIGS. 1 through 10 represents environmental subject matter and forms no part of the claimed design. All text shown in FIGS. 1 through 10 is shown in broken lines. The greyscale fill appearing in the some of the icons shown in the second and fourth images of each embodiment signifies that those icons are darkened relative to the icons having greyscale fill in the first and fifth images of each respective embodiment. The greyscale fill appearing in the some of the icons shown in the third image of each embodiment signifies that those icons are darkened relative to the icons having greyscale fill in the second and fourth images of each respective embodiment.
